UNITED STATES PATENT OFFICE.

ROBERT F. HENDERSHOT, OF WEST PITTSBURGH, PENNSYLVANIA, ASSIGNOR TO GARLAND MANUFACTURING COMPANY, OF WEST PITTSBURGH, PENNSYLVANIA, A CORPORATION OF PENNSYLVANIA.

PROCESS OF PICKLING AND APPARATUS THEREFOR.

Application filed June 27, 1921. Serial No. 480,553.

To all whom it may concern:

Be it known that I, ROBERT F. HENDERSHOT, a citizen of the United States, residing at West Pittsburgh, in the county of Lawrence and State of Pennsylvania, have invented a new and useful Improvement in the Process of Pickling and Apparatus Therefor, of which the following is a full, clear, and exact description.

10 My invention relates to the process of pickling and apparatus therefor and is particularly applicable to the pickling of pipe, rods, bars and sheets.

An object of my invention is such a device 15 which is simple in construction and efficient in operation.

A further object of my invention is such a device wherein the articles being treated are alternately immersed in the pickling 20 solution and exposed to the atmosphere.

A further object of my invention is such a device wherein the basket for the articles being treated may be removed from the container for the pickling solution and another 25 basket placed in position in the container without the necessity of loading the articles being treated in the basket in place.

A further object of my invention is such a device wherein the necessary oxidation 30 may be secured without the necessity of bubbling air or steam through the solution.

Further objects of my invention will be apparent to those skilled in the art upon reading the following description in connection 35 with the drawings illustrating one form of my invention, and in which:

Figure 1 is a plan view of a device embodying my invention;

Figure 2 is a sectional view on the line 40 II—II of Figure 4;

Figure 3 is a side elevation;

Figure 4 is a sectional view on the line 45 IV—IV of Figure 1; and

Figures 5 and 6 are detail views.

Referring to the drawings, the device 50 comprises a container 1 for the pickling solution. This container may be of any desired shape but is preferably provided with a false bottom 2 so that a smaller amount of solution may be used.

The container 1 is provided on its sides with journals 3, which carry a shaft 4 from which is suspended a basket for containing the articles under treatment. This basket

comprises a longitudinal member 5 in the 55 ends of which are fastened the shafts 6. These shafts carry U-shaped members 7. At the lower end of each of the members 7 is an inwardly extending horizontal flange 8, upon which rest the ends of the pipes 9. A perforated plate 10 is placed in each of the members 7 so as to prevent the pipes 9 or other articles from sliding longitudinally when the basket is oscillated as hereinafter explained. In order to prevent the members 60 7 from spreading apart at the bottom and allowing the pipes or other articles to fall out of the basket, tie rods 11 are provided, one end of each of which is fastened to the members 7 by any suitable arrangement such 65 as passing through an opening 12, as shown in detail in Figure 5. The tie rods 11 have the function of holding the members 7 at substantially fixed distance from each other. 70

The shaft 4 has one member of a coupling 75 13 thereon, as shown in Figures 1 and 4. The other member of the coupling 13 is connected with a shaft 14. The shaft 14 has a crank 15 fastened thereto. Attached to the crank is a link 16 which is connected at its 80 other end to a crank 17 which is fastened onto a power shaft 18 operated by any suitable power device. The shaft 18 is journalled at 19.

The shaft 14 has a similar coupling member 85 on the other end thereof which cooperates with a member on a second shaft 4 to constitute the coupling 20. The structure of the two tanks and baskets shown in Figure 4 is identical and the preceding description 90 of one of them is sufficient for both.

The couplings 13 and 20 are operated by the levers 21 and 22, respectively. Any form of coupling may be used.

The longitudinal member 5 is provided 95 with means 23, such as eye bolts, so that the basket containing the articles under treatment may be removed with the articles therein by lifting the same out of the open journals 3.

The container may be of any desired construction and of any suitable material and the basket may be operated by any mechanism other than the specific arrangement shown.

The operation of my invention is as follows:

The container is filled with pickling solu-

tion to the desired point, and by reason of the false bottom the desired depth of solution may be secured with a minimum amount thereof.

5 A basket containing the articles to be treated is then placed in position, the arrangement preferably being such that the solution covers all of the articles in the basket when the basket is standing in the position shown in full lines in Figure 2, that is to say, horizontally. In the pickling of pipe or other articles, it is necessary in order to get the maximum benefit of the pickling solution to subject the articles to an oxidizing environment. This is accomplished in my process and apparatus by moving the basket around the shaft 4 so that the ends of the pipes are alternately submerged and exposed to the atmosphere. This operation 10 not only subjects the articles alternately to the pickling solution and atmosphere but agitates the solution so that a considerable amount of air is entrained in and absorbed by the solution, as a result of which the 15 maximum chemical reaction and pickling is secured. The apparatus for moving the basket is the power shaft 18 and the connections 15, 16 and 17, which will be clearly understood from Figures 1, 3 and 4. A 20 clutch or coupling mechanism is provided so that each of the connections 15, 16 and 17 may operate two baskets either simultaneously or at separate times. As soon as the pickling process of the articles in one 25 of the baskets is completed, the clutch is thrown out of engagement and that basket may be lifted out of the solution container by a crane or other suitable means. Another basket containing similar or other 30 articles may then be substituted and the process repeated, it being observed that a basket may be loaded with articles while the articles in another basket are being treated, so that maximum efficiency and production 35 are secured from each pickling container.

While I have shown a basket arranged for containing pipe, it will be understood that a basket of any suitable construction may be employed for holding pipe or any 40 other article to be subjected to the pickling process.

From the foregoing it will be evident that the solution not only effectively pickle the outside of the pipe, but by reason of the 45 fact that the ends of the pipe are alternately lowered and raised, the solution moves rapidly through the interior of the pipe and therefore effectively treats the inside also.

This effective treatment is accomplished 50 without any special means for incorporating air into the solution as is necessary in many pickling processes as used heretofore.

My invention has many advantages, among which are that the device is simple 55 and inexpensive; that the spent pickle in

contact with a stationary article is replaced by live pickling solution; that attrition or scouring is present by reason of the flow of the pickling solution over and through the pipes, or other articles being treated; 70 that both a chemical and mechanical action are produced on the surface being treated; that the necessary oxidizing agent is given access to the articles; that the basket containing the articles to be treated may be 75 readily placed in position and removed and therefore loaded and unloaded at the proper points for those operations with the result that greater efficiency and greater production may be secured. 80

Many other advantages will be apparent to those skilled in the art and need not be recited here.

I claim:

1. A pickling device comprising a solution tank, a basket journaled on the sides of the tank and adapted to receive lengthwise thereof the articles to be pickled, and means for moving the basket to dip its ends alternately into solution in said tank to produce a movement of the solution lengthwise of the articles. 85

2. A pickling apparatus comprising a plurality of solution tanks, a pivoted basket for each tank, means connecting said baskets for operating said baskets simultaneously, and means for disconnecting either of said baskets from said operating means while operating the other. 95

3. The process of pickling pipe which 100 consists in alternately dipping the ends of the pipe into a pickling solution and allowing the solution to run through the pipe.

4. The process of pickling pipe, which comprises submerging the ends of a pipe alternately in a pickling bath and raising the ends thereof alternately out of the bath to allow the pickling fluid to run through the pipe first in one direction and then in the opposite direction. 105

5. The process of pickling pipe, which comprises imparting a mechanical cleaning action to the interior and exterior surfaces of the pipe by flowing the pickling fluid through and around the pipe during the treatment while alternately exposing portions of the pipe to the atmosphere and submerging such portions in the pickling fluid. 115

6. The process of pickling pipe, which comprises producing a turning movement of a pipe about a transverse axis to cause a flow of the pickling fluid through the pipe. 120

7. In a pickling device, a container for the pickling solution, means for supporting therein the articles to be pickled, and means for periodically raising portions of the articles above the bath in the container and then submerging the same in said bath. 125

8. In a pickling device, a container for the pickling solution, means for supporting 130

therein the articles to be pickled, and means for periodically raising one end of the articles above the bath in the container and then submerging the same in the bath to produce 5 a flow of pickling fluid together with entrained air longitudinally of the articles.

9. In a pickling device, a container for the pickling solution, means for supporting therein below the level of the pickling fluid 10 the articles to be pickled, and means for alternately raising certain portions of the articles above the level of the bath and then submerging the same in the bath.

10. In a pickling apparatus, a container, 15 an article basket comprising a support journaled on said container, members pivotally depending from said support, means pivotally connected to the lower ends of said members for holding said members in fixed 20 relation to each other, and means carried by

said pivoted members for holding the articles under treatment.

11. In the art of pickling, the step consisting in alternately submerging portions of the articles in a pickling solution and 25 then exposing said portions to the atmosphere in continuous succession.

12. Pickling apparatus for pipe, comprising a pickling bath, a basket adapted to receive lengthwise thereof the pipe to be 30 pickled, means for supporting said basket for oscillation about a transverse axis, and means for oscillating said basket to alternately dip the opposite end portions of the pipe into the bath and raise such portions out of the bath.

In testimony whereof, I have hereunto set my hand.

ROBERT F. HENDERSHOT.
